SOIL WARMING DEVICE

Andrew Hallum, Springfield, Mo.

Application October 28, 1953, Serial No. 388,857

4 Claims. (Cl. 47—19)

5 The shield 73 is also provided with a partition 78 and a cap 79 having a flange 80 on its end is positioned on the end of the shield. The flange 80 of the cap may be provided with slots 81 which provide means for the escape of gases of combustion as well as for the inlet of air to support combustion, or as illustrated in Figure 7, a flange 82 similar to the flange 80 may be provided with spaced openings 83.

10 From the foregoing, it is apparent that with the shield 73 surrounding a portion of the wick tube 72 and with the end of the wick tube positioned in a hill 74, heat will be supplied to the surrounding area of the hill to seeds therein as the wick 75 burns, the seeds being indicated by the numeral 84.

15 The cover 71 of the tank 70 may be provided with spaced openings 85 which provide vents as shown in Figure 2. The shield 73 may also be provided with a base 86 whereby a complete enclosure is provided around the section of the wick tube positioned in the hill.

20 The object of the invention is to provide a heater for expediting the growth of watermelons and the like which are subject to the damaging effects of frost or cold weather, the present invention providing a warming device especially suitable during the incubation period of the seeds. 25 Another object of the invention is to provide a heating apparatus wherein the fuel tank is placed above the ground, there being a shield positioned around the wick tube or burner. 30 A further object of the invention is to provide a heating apparatus which is extremely simple and inexpensive to manufacture. 35 Other objects and advantages will be apparent during the course of the following description.

In the accompanying drawings, forming a part of this application, and in which like numerals are used to designate like parts throughout the same:

Figure 1 is a longitudinal sectional view taken through the burner and showing the fuel tank and wick tube in elevation, the fuel tank being positioned above the ground, and there being a U-shaped shield positioned around the wick tube or burner. 40

Figure 2 is a sectional view taken on the line 2—2 of Figure 1.

Figure 3 is a plan view showing the shield to be positioned around the burner.

Figure 4 is a sectional view taken on the line 4—4 of Figure 1.

Figure 5 is an enlarged view similar to Figure 4, showing a cap on the upper open end of the shield.

Figure 6 is a plan view of the cap shown in Figures 4 and 5.

Figure 7 is a plan view illustrating a modified cap wherein there is provided openings instead of slots.

Figure 8 is a plan view showing a further modification of the invention.

Referring in detail to the drawings, there is shown a fuel tank which is indicated by the numeral 70, and the fuel tank 70 is provided with a cover 71, the fuel tank 70 being positioned on the ground. A wick tube 72 extends from one side of the tank, and the wick tube includes a horizontally disposed straight portion and a vertical portion, there being a U-shaped shield 73 which is positioned around a portion of the wick tube 72. Thus, with the tube and shield positioned in a hill 74, heat will be supplied to soil in the hill as the wick 75 which extends from the tube 72 burns. The wick 75 is positioned adjacent the upper end of the compartment 88.

The shield 73 is provided with a closure plate 76 through which the tube 72 extends, and a cover 77 is provided on the upper end thereof.

2

5 The shield 73 is also provided with a partition 78 and a cap 79 having a flange 80 on its end is positioned on the end of the shield. The flange 80 of the cap may be provided with slots 81 which provide means for the escape of gases of combustion as well as for the inlet of air to support combustion, or as illustrated in Figure 7, a flange 82 similar to the flange 80 may be provided with spaced openings 83.

10 From the foregoing, it is apparent that with the shield 73 surrounding a portion of the wick tube 72 and with the end of the wick tube positioned in a hill 74, heat will be supplied to the surrounding area of the hill to seeds therein as the wick 75 burns, the seeds being indicated by the numeral 84.

15 The cover 71 of the tank 70 may be provided with spaced openings 85 which provide vents as shown in Figure 2. The shield 73 may also be provided with a base 86 whereby a complete enclosure is provided around the section of the wick tube positioned in the hill.

20 The object of the invention is to provide a heater for expediting the growth of watermelons and the like which are subject to the damaging effects of frost or cold weather, the present invention providing a warming device especially suitable during the incubation period of the seeds. 25 Another object of the invention is to provide a heating apparatus wherein the fuel tank is placed above the ground, there being a shield positioned around the wick tube or burner. 30 A further object of the invention is to provide a heating apparatus which is extremely simple and inexpensive to manufacture. 35 Other objects and advantages will be apparent during the course of the following description.

35 In the accompanying drawings, forming a part of this application, and in which like numerals are used to designate like parts throughout the same:

Figure 1 is a longitudinal sectional view taken through the burner and showing the fuel tank and wick tube in elevation, the fuel tank being positioned above the ground, and there being a U-shaped shield positioned around the wick tube or burner. 40

Figure 2 is a sectional view taken on the line 2—2 of Figure 1.

Figure 3 is a plan view showing the shield to be positioned around the burner.

Figure 4 is a sectional view taken on the line 4—4 of Figure 1.

Figure 5 is an enlarged view similar to Figure 4, showing a cap on the upper open end of the shield.

Figure 6 is a plan view of the cap shown in Figures 4 and 5.

Figure 7 is a plan view illustrating a modified cap wherein there is provided openings instead of slots.

Figure 8 is a plan view showing a further modification of the invention.

I claim:

1. A seed warming device comprising a fuel tank adapted to be positioned above ground level, a wick tube extending from said tank and including a horizontally disposed straight portion and a vertically disposed upright portion positioned in the ground, a shield positioned around a portion of said wick tube, a partition arranged in said shield, and a cap mounted on an end of said shield and including a flange provided with a plurality of openings for the passage therethrough of gases of combustion.

2. A seed warming device comprising a fuel tank adapted to be positioned above ground level, a wick tube extending from said tank and including a horizontally disposed straight portion and a vertically disposed upright portion positioned in the ground, a shield positioned around a portion of said wick tube, a partition arranged in said shield, and a cap mounted on an end of said shield and including a flange provided with a plurality of openings for the passage therethrough of gases of combustion, and a cover mounted on said tank, there being a plurality of vent openings arranged in said cover.

3. A seed warming device comprising a fuel tank adapted to be positioned above ground level, a wick tube extending from said tank and including a horizontally disposed straight portion and a vertically disposed upright portion positioned in the ground, a shield positioned around a portion of said wick tube, a partition arranged in said shield, a cap mounted on an end of said shield and including a flange provided with a plurality of openings for the passage therethrough of gases of combustion, a cover mounted on said tank, there being

a plurality of vent openings arranged in said cover, a vertically disposed closure plate extending between the ends of said shield and provided with an opening for the projection therethrough of the horizontal portion of said tube.

4. The apparatus as described in claim 3, and further including a base mounted below said shield.
